UNITED STATES PATENT OFFICE

2,503,501

SMOKER'S ACCESSORY

Charles Victor Lutz, Hollywood, Calif.

Application December 17, 1946, Serial No. 716,808

1 Claim. (Cl. 131—243)

1

This invention relates to new and useful improvements and structural refinements in smokers' accessories, and the principal object of the invention is to provide a device of the character herein described, which may be conveniently and effectively employed for removing the scale from the bowl of the pipe and for packing the tobacco in the bowl.

A further object of the invention is to provide a tool for the purposes above described which is conveniently associated with the tobacco pouch.

Another object of the invention is to provide a smoker's accessory which is simple in construction, pleasing in appearance and which may be easily and conveniently manipulated.

An additional object of the invention is to provide a smoker's accessory which will not easily become damaged and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a side elevation of the invention including the tobacco pouch.

Figure 2 is a cross-sectional view of the scale removing and tobacco packing tool per se, and

Figure 3 is a cross-sectional view, taken substantially in the plane of the line 3—3 in Figure 1.

Like characters of reference are used to designate like parts in the specification and throughout the several views.

Referring now to the accompanying drawings in detail, the invention as a whole, is designated generally by the reference character 10, the same consisting primarily of a tobacco packing and scale removing tool designated by the general reference character 11.

The tool 11 embodies in its construction a substantially tubular sleeve 12 including a longitudinal bore 13 and provided at one end with a counterbore 14. A pair of disc-like heads 15 and 16 are formed at the ends of the sleeve 12, as will be clearly apparent.

A stem 17 is slidably positioned in the bore 13 and one end of the stem terminates in a pointed extremity 18. An annular shoulder 19 is formed on the stem 17 adjacent the extremity 18 and a further shoulder 20 is provided adjacent the remaining end of the stem, as is best shown in Figure 2. The shoulder 19 is receivable in the counterbore 14, as will be hereinafter more fully described.

2

The end-portion of the stem 17 equipped with the shoulder 20 terminates in a spherical member 21 which is removably receivable in a complementary socket 22. This socket is fastened to one end of a ball and link chain 23, whereby the entire tool 11 may be attached to a conventional key-ring (not shown) or the like.

However, for purposes of added convenience, the tool 11 may preferably be associated with a conventional tobacco pouch 24 equipped with the usual slide fastener 25. In such instance, the free end of the chain 23 may be connected to the pull tab 26 of the fastener 25 and the pouch 24 may be provided on the outer surface thereof with a substantially cylindrical jacket 27.

More specifically, this jacket may assume a substantially U-shaped cross-sectional configuration and may be provided with suitable longitudinally extending flanges 28 to facilitate attachment thereof to the pouch.

One end of the jacket 27 may be closed as indicated at 29, while the aforementioned tool 11, as a whole, may be inserted into the jacket through the remaining, open end of the latter.

It will be observed that the jacket 27 will provide a convenient storage compartment, as it were, for the tool 11, or alternatively, if simplicity of construction is to be attained, the provision of the jacket may be dispensed with and the tool 11 may be positioned directly in the pouch 24.

With particular reference to the tool 11 per se, it will be found that the sleeve 12 may be slid on the stem 17 between the limits of the shoulders 19 and 20, that is, between one extreme when the shoulder 20 contacts the head 15 and the opposite extreme when the shoulder 19 contacts the inner end 29 of the counterbore 14. Matters are so arranged that in the last mentioned instance, the end 18 is disposed within the counterbore 14 as indicated by the phantom line 30, thereby permitting the head 16 to be used for packing the tobacco in the pipe bowl.

On the other hand, when the extremity 18 is projected from the sleeve 12 as indicated by the full line in Figure 2, the extremity may be effectively employed for removing the scale from the bowl of the pipe.

The removable connection afforded by the member 21 and the socket 22 will, of course, facilitate the use of the tool 11 independently of the chain 23 and of the associated pouch 24.

It is believed that the advantages and use of the invention will be clearly apparent from the foregoing disclosure, and accordingly, further de-

scription thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

The combination of a pouch including a pair of side walls having separable contiguous edges to afford an entrance opening, a slide fastener provided on said edges for closing said opening and including a pull tab, an elongated pocket provided on the outer surface of one of said side walls and having a closed end and an open end, a tool removably positioned in said pocket and projecting outwardly from the open end of the latter, and a flexible fastening element connected at one end

thereof to the projecting portion of said tool and having its remaining end secured to said pull tab, whereby said tool may afford a handle for actuating said tab.

CHARLES VICTOR LUTZ.
